UNITED STATES PATENT OFFICE.

WILLIAM H. FAUBER, OF CHICAGO, ILLINOIS.

DESIGN FOR A SPROCKET-WHEEL FOR BICYCLES.

SPECIFICATION forming part of Design No. 28,215, dated January 25, 1898.

Application filed November 8, 1897. Serial No. 657,894. Term of patent 7 years.

To all whom it may concern:

Be it known that I, WILLIAM H. FAUBER, a citizen of the United States, residing in the city of Chicago, county of Cook, and State of Illinois, have invented and produced a new and original Design for a Sprocket-Wheel for Bicycles, of which the following is a specification, reference being had to the accompanying drawings, forming a part hereof.

10 In said drawings, Figure 1 is a view in side elevation of a sprocket-wheel made in accordance with my design. Fig. 2 is a sectional view taken on a straight line through the center of the wheel and one of the spokes thereof.

15 A sprocket-wheel made in accordance with my design consists of an outer circular rim, an inner circular ring or hub concentric with said rim, and a plurality of spokes or arms extending radially between said hub and rim

20 and spaced at equal angular distances apart. Said rim is provided on its periphery with a plurality of openly-spaced radial projections or sprocket-teeth. The said spokes are five in number and are made much wider at their

25 inner than at their outer ends, their inner ends being so wide that the side margins of the adjacent spokes meet or nearly meet each other at the outer margin of the inner ring or hub, thereby giving to the hub and spokes as

30 a whole the appearance of a five-pointed star. The side edges of each spoke are straight, and those of adjacent spokes are joined near the hub by a concave curve, while said side margins are joined to the inner margin of the rim

35 by a similar concave curve. Each spoke is, moreover, pierced by a plurality of circular apertures made of gradually-lessening size from the inner to the outer end of the spoke,

the apertures in each spoke being arranged in a straight radial line along the center of 40 the spoke with the largest aperture near the inner end of the spoke and the smallest one adjacent to or partially within the rim of the wheel.

The central part of the wheel, comprising 45 the spokes, the inner ring or hub, and the inner part of the rim, is made of less thickness than the outer or marginal part of the rim, upon which the sprocket-teeth are formed, this reduction in thickness of the inner part 50 of the rim forming thereon an annular rabbet or recess of concave form. The wheel is also made of slightly concave or dished form, as clearly seen in the sectional view.

The essential or characteristic feature of 55 my design is embraced in a wheel having radial spokes which are of such width at their inner ends that the side margins of the adjacent spokes meet or nearly meet each other at the intersection thereof with the outer margin of the hub and which gradually taper toward the outer rim, at the intersection with which they are of considerably less width than at their inner ends, and in which each of the spokes is pierced by a plurality of circular 60 apertures made of gradually-lessening size from the inner to the outer end of the spoke and arranged on a straight radial line along the center of the spoke.

I claim as my design—
70 The design for a sprocket-wheel for bicycles, substantially as shown and described.

WILLIAM H. FAUBER.
